(57) **CLAIM**

The ornamental design for a patient overlay for a radiation couch, as shown and described.

DESCRIPTION

FIG. 1 is a perspective view of a patient overlay for a radiation couch incorporating the design.

FIG. 2 is a top view thereof.

FIG. 3 is a bottom view thereof.

FIG. 4 is a right-side view thereof.

FIG. 5 is a left-side view thereof.

FIG. 6 is a front view thereof; and,

FIG. 7 is a back view thereof.

The broken lines shown in the drawings illustrate portions of the patient overlay for a radiation couch that form no part of the claimed design.

1 Claim, 5 Drawing Sheets

UNITED STATES PATENT AND TRADEMARK OFFICE
CERTIFICATE OF CORRECTION

PATENT NO. : D872,864 S
APPLICATION NO. : 29/635182
DATED : January 14, 2020
INVENTOR(S) : Francois Marcil

Page 1 of 1

It is certified that error appears in the above-identified patent and that said Letters Patent is hereby corrected as shown below:

On the Title Page

In item (73), in "Assignee", in Column 1, Line 1, delete "LTD," and insert --LTD.,-- therefor

Signed and Sealed this
Fourteenth Day of July, 2020
